UNITED STATES PATENT OFFICE.

EDWARD E. CHALBERG, OF CHAPPELL, NEBRASKA, ASSIGNOR OF ONE-HALF TO A. B. OZMAN, OF CHAPPELL, NEBRASKA.

COMPOUND INTERNAL-COMBUSTION ENGINE.

1,219,082.

Specification of Letters Patent. Patented Mar. 13, 1917.

Application filed April 9, 1913. Serial No. 760,064.

To all whom it may concern:

Be it known that I, EDWARD E. CHALBERG, a citizen of the United States, residing at Chappell, in the county of Deuel and State of Nebraska, have invented certain new and useful Improvements in Compound Internal-Combustion Engines; and I do hereby declare the following to be a full, clear, and exact description of the invention, such as 10 will enable others skilled in the art to which it appertains to make and use the same.

This invention relates to new and useful improvements in compound internal combustion engines and has for its object to provide a device which is adapted to receive the exhaust gases from an internal combustion engine cylinder and expand the same into a cylinder of larger capacity, and by this means eliminate the noise usually accompanying the exploding of gases within the cylinders of an internal combustion engine and increase the power developed.

Another object of my invention is to provide a device which will serve as an auxiliary low pressure engine operating in connection with the main engine.

A still further object of my invention is to provide a device which will be cheap in construction, simple in operation and effective in use.

With the above and other objects in view I will now proceed to describe my invention in the following specification and accompanying drawings, in which—

35 Figure 1 is a side elevation of one form of my improved auxiliary motor;

Fig. 2 is a top plan view of Fig. 1;

Fig. 3 is a sectional view taken on line 3—3 of Fig. 1;

40 Fig. 4 is a diagrammatic view of a four-cylinder internal combustion engine of the usual construction, showing my auxiliary motor applied thereto;

Fig. 5 is a top plan view of a safety valve 45 which is used in connection with my auxiliary motor;

Fig. 6 is a sectional view of the same taken on line 6—6 of Fig. 5;

50 Fig. 7 is a detail perspective view of the slide valve which I use at the exhaust side of my improved auxiliary motor;

Fig. 8 is a longitudinal section of Fig. 7;

Fig. 9 is a diagrammatic view of a six-cylinder internal combustion engine, show-

ing the other form of my improved auxiliary motor;

Fig. 10 is a top plan view of the auxiliary motor which I use with the six-cylinder motor; and

Fig. 11 is an end elevation showing the arrangement of the slide valves.

Referring to the drawings by characters of reference, 1 indicates a cylinder of my improved auxiliary motor which is provided adjacent each end, with inlet ports 2. Slide valves 3 are located adjacent the ends of the cylinders and are adapted to be connected with an exhaust pipe 4. The inlet ports 2 are provided with couplings 5 to which are attached the exhaust pipe 6 of each pair of cylinders of the gas engine. The slide valves 3 are preferably composed of the slide 7 having a port 8 adapted to register with the opening 9, which enters the cylinder and is connected with the exhaust pipe 4.

At one end of the cylinder 1 I preferably provide guides 10 which are adapted to receive the crosshead 11, to which is attached the connecting rod 12 and the piston rod 13. The connecting rod 12 is provided at its outer extremity with a bearing 14 which is adapted to surround the crank shaft 15 when my device is in operation. The slides 7 of the slide valves 3 are operated by means of the eccentric 16 carrying the eccentric strap 17, which is connected to the pitman 18 and, as will be seen upon referring to the drawings, as the crank shaft rotates the pitman will cause the slide 7 of the valve 3 to reciprocate and bring the port 8 in alignment with the port 9.

Suitably mounted adjacent the ends of the cylinder 1 I provide safety valves 19, which comprise the valve seat 20, the valve 21, the stem 22 and a spider 23, which spider is provided with an aperture intermediate its ends, which is adapted to receive the valve stem 22. A coil spring 24 is adapted to contact between the spider and the valve 21 and cause the same to firmly seat against the valve seat 20. It will be clearly seen that when the pressure in the cylinder of the auxiliary motor becomes too great the valve 21 will rise from seat 20 and allow the excess pressure to escape, thereby eliminating any danger of explosion. A relief valve 25, consisting of the body portion 26, the recip-

roating slides 27, and the rod 28 is provided, the rod being adapted to be operated in any suitable manner at the time the engine is being cranked. This valve 25 is provided with the outlet port 29, which is adapted to register with a port in the cylinder and prevent any vacuum or compression being formed therein at the time the motor is being started. This port 29 is adapted to align with the port 30 in the reciprocating member 27 when the device is in use.

A four-cylinder internal combustion engine indicated generally at 31 is provided with cylinders 32, 33, 34 and 35, which in turn are provided with the usual pistons 36 and connecting rods 37. This engine is provided at one end with the usual crank 38 which carries the collars 39 between which I provide a sleeve 40, to which the rod 28 of the relief valve is attached. At the opposite end of the crank shaft indicated at 41 I preferably provide a beveled gear 42, which is adapted to coöperate with the beveled gear 43 on shaft 15 of my auxiliary motor, whereby the same is put in operation. A piston 43 is provided in the cylinder 1 of my auxiliary motor which is so timed that it will move in the opposite direction to that of a piston of the gas engine.

As clearly shown in Fig. 4, the cylinder 32 is just beginning to exhaust, the gases passing outwardly through the usual valves into the pipe 6. As the piston advances the gases are forced out through the pipe 6 into the cylinder 1 of my auxiliary motor at a point indicated by numeral 44. It will be seen that upon this same stroke cylinder 35 is compressing and cylinder 33 is firing. When the crank shaft of cylinder 33 reaches its lowermost extremity the exhaust port opens and the exhaust gases pass outwardly through the pipe shown at 45 and into the cylinder 1 of my improved auxiliary motor at a point indicated at 46. By that time the piston 43 will have reached the other extremity of the cylinder 1, and as the gas enters the cylinder at 46 the piston 43 will start upon its return to the original position. At the same time that the piston starts upon its return a slide valve in the opposite end of said piston indicated at 3 opens and allows the gases which were expanded on the previous operation into the opposite end of the cylinder to escape through the exhaust pipe 4. As is clearly illustrated in the drawings, the next cylinder in turn will exhaust into the end 44 of the cylinder 1 of my improved muffler, and the next cylinder in turn will exhaust into the end 46, this operation being continued until the motor is stopped. As the gases are expanded into the cylinder 1 before they are exhausted to the atmosphere, it will be clear that they will have lost considerable of their explosive force, and by the time that they are ex-

hausted into the atmosphere they will be substantially the same pressure as that of the atmosphere and, consequently, the majority of the noise usually accompanying the exploding of the gas in a gas engine will be eliminated.

In Figs. 9, 10 and 11 of the drawings I have shown a type of auxiliary motor to be used in connection with a six-cylinder internal combustion engine. This form consists of cylinders 47, 48 and 49, these cylinders being made similar to the cylinders of an internal combustion engine and provided with the pistons 50 and the connecting rods 51. A slide valve of the construction similar to the one previously described is provided for each of said cylinders, as indicated at 52, and is connected to the crank shaft by means of the eccentric rod 53, which is operated by the eccentric 54 keyed to the crank shaft of the auxiliary motor. This motor is preferably connected to the engine shaft by means of a flange coupling 55. The usual relief valves indicated at 56 are provided and are operated by means of the rocker arm 57, which is pivoted as shown at 58 and operated by means of the rod 28. The slide valves 52 are connected to the exhaust pipes similar to the valves previously described. The cylinders of the engine are indicated in the rotation of firing by means of the characters *a*, *b*, *c*, *d*, *e* and *f*. Each pair of cylinders is connected to its respective cylinder of the auxiliary motor by means of the pipes 59, 60 and 61; as is clearly illustrated in Fig. 9, the cylinder *e* is exhausting the gases passing through the usual exhaust valve into the pipe 59 and thence into the cylinder 47 of the auxiliary motor. As the piston in cylinder *e* passes upward the gases are forced into the enlarged cylinder 47 and against the piston 50, which upon descending allows the gas to expand into the larger cylinder, and thereby takes up considerable of its force. As the piston in cylinder 47 starts on its upward course the valve 52 opens and allows the exhaust gases to pass out through the exhaust pipe. The next cylinder to exhaust being *a*, the gases will pass upwardly through the valves into the exhaust pipe 60 and into the cylinder 48 of the auxiliary motor and the same operation will be gone through. The following cylinder, *b*, will exhaust through the pipe 61 into the auxiliary motor cylinder 49. Then, as the auxiliary motor exhausts through the slide valve 52 into the exhaust pipe, the next cylinder in turn, *c*, will exhaust into the cylinder 47 of the auxiliary motor, and this operation will be continued until each cylinder has fired and exhausted and the auxiliary motor has taken up the excess pressure which will perform in the same manner as a compound steam engine and thereby increase the power for the same amount of energy used.

While in the foregoing I have shown and described the preferred embodiment of my invention, it is to be understood that I can change the arrangement and construction of 5 the parts without in any way departing from the spirit and scope of the claim.

Having fully described my invention what I claim is:

The combination with an explosive engine 10 including a plurality of cylinders, pistons operable within the cylinders, a crank shaft, connecting rods connecting the pistons with the crank shaft, the cylinders being provided with exhaust ports and a cranking device 15 for cranking the engine, of a plurality of low pressure cylinders, pistons operable in the low pressure cylinders, a crank shaft connected to the crank shaft of the engine, connecting rods connecting the last men- 20 tioned crank shaft with the pistons in the low pressure cylinders, the said pistons in

the low pressure cylinders being in opposed relation to the pistons in the engine cylinders, the low pressure cylinders having intake ports therein, pipes connecting the exhaust ports of the engine cylinders with the intake ports of the low pressure cylinders, relief valves on the low pressure cylinders, a rod connecting the relief valves for simultaneously operating the same and means connecting the rod with the cranking device whereby when said cranking device is moved into operative position with relation to the crank shaft the rod will be moved to open the relief valves. 25 30 35

In testimony whereof I affix my signature in presence of two witnesses.

EDWARD E. CHALBERG.
